UNITED STATES PATENT OFFICE.

SIGURD JAHR HOFF, OF NEW YORK, N. Y.

WINDOW LOCK.

Application filed May 16, 1922. Serial No. 561,313.

To all whom it may concern:

Be it known that I, SIGURD JAHR HOFF, a citizen of the United States, residing at New York, in the county of New York and State of New York, have invented certain new and useful Improvements in Window Locks, of which the following is a specification.

This invention relates to locks, more particularly to window locks, and has for its main object the provision of a lock which will when manipulated securely lock a pair of slide windows in the closed position in such a way so that they cannot be opened by a pry bar or similar burglar's tool.

Another object is to provide with the device a means for jamming the contacting surfaces of the windows to each other so as to prevent their rattling during a heavy wind.

The above and other objects will become apparent in the description below in which characters of reference refer to like-named parts in the drawing.

Referring briefly to the drawing, Figure 1 represents a front elevation of a window in closed position.

Figure 2 is a sectional side elevational view taken on the line 2—2 of Figure 1.

Figure 3 is a fragmentary enlarged elevational view of the upper rail of the lower sash showing the means for moving the locking bolt.

Figure 4 is a sectional side elevational view of the same, taken on line 4—4 of Figure 3.

Figure 5 is a fragmentary enlarged elevational view of the lower rail of the upper sash showing the locking slot formed therein.

Figure 6 is a top plan view of the same.

Describing the drawing more in detail, the numeral 10 indicates the upright members of a window frame which are joined to each other by horizontal members 11. An upper sash 12 and a lower sash 13 are slidably mounted within the frame, one adjacent the other. These sashes can be the usual construction and the locking device interferes with no part of its function or operation.

The lower sash 13 has a longitudinal recess 14 formed in its upper horizontal rail 15 and is provided with a series of gear teeth 16 which run thruout the upper surface of the recess. Said recess 14 provides

a housing chamber for a small pinion 17 which has a hole 18 centrally disposed therein and is adapted to rotatably receive a locking bolt 19. This bolt 19 extends thru a slot 20 which permits a linear travel of pinion 17 when the latter is rotated while the locking bolt projects rearward from the pinion hole 18 thru the slot 20, extending somewhat beyond, and has a relatively large square flanged head 21 formed at its end.

An annular knurled hand knob 22 formed integral with the pinion 17 extends therefrom and is adapted to rotate latter when turned. The threaded end of locking bolt 19 projects from the thumb knob 22 and is firmly secured in place on the pinion by lever being applied to wing nut 23.

The lower horizontal rail 24 of the upper sash 12 has an angular slot 25 open at one end, the bottom of said open end corresponding to the extreme end of travel of the locking bolt 19 in the lower sash. Said slot 25 extends downward changing its course to horizontal and is of such length as to register with slot 20 in the lower sash when both sashes 12 and 13 are in closed position. A sunken channel 26 formed within frame 24 behind the slot 25 receives the square head 21 of the locking bolt when both sashes are closed.

In use, and when securely locking the sashes in closed position, after the upper sash 12 is in its proper position, the lower sash 13 is lowered after the locking bolt 19 is moved to the end of 20 (this position being indicated in Figure 3). As the lower sash is closed while the bolt is in this position, the flanged head 21 thereof will enter channel 26 and complete the vertical length of travel when the sash is completely closed. Loosening the winged nut 23 and rotating the knurled thumb knob 22 will urge or slide the locking bolt 19 to the locking end of the slot 20. During the travel of the locking bolt 19, the flanged head 21 thereof will engage and ride upon the inclined surface 28 of the sunken channel 26. This will draw the adjacent surfaces of the upper and lower sashes toward each other in a sort of jam fit and thus completely seal the window opening and also prevent any rattling which would be bound to occur, during a strong wind, if the sashes were separated. Tightening of the wing nut 23 will obviously secure

the locking bolt in the adjusted position and prevent a person from feeding the locking bolt to the releasing end of the slot.

I claim;

- 5 1. In combination with a pair of slide sashes, a means for releasably locking both sashes in the closed position comprising an upper sash with a longitudinal slot therein and provided with an angular exit slot at 10 one end thereof, said upper sash having a sunken channel registering with the said slots, an inclined surface formed on one side of the sunken channel and means carried within the channel for locking the upper and lower sashes to each other when in 15 the closed position.
2. In combination with a pair of slide sashes, a means for releasably locking both sashes to each other in the closed position 20 comprising an upper sash having a longitudinal slot, and an exit slot at one end of the latter, and a sunken channel registering with the said slots, a lower sash having a longitudinal slot and an open recess formed 25 therein which register with the slot in the upper sash, a locking bolt engaging said

slots, a square headed flange slidable in said channel, means for locking the locking bolt in the longitudinal slots and means for moving said locking bolt laterally in the said slots.

3. In combination with a pair of slide sashes, a means for releasably locking both sashes in the closed position comprising an upper sash having a longitudinal slot, and an exit slot at one end of the latter, and a sunken channel registering with the said slots, a lower sash having a longitudinal slot and an open recess formed therein which register with the slot in the upper sash, 40 rack teeth on one surface of the open recess, a pinion in said recess and engaging said rack teeth, a knurled thumb knob formed integral with said pinion, a square headed locking bolt receiving said pinion revolvably thereon, said pinion when rotated adapted to move the bolt along the slot and means for securing said locking bolt in the longitudinal slots.

In witness whereof I affix my signature. 50

SIGURD JAHR HOFF.
